UNITED STATES PATENT OFFICE.

ROBERT E. BROWN, OF OLEAN, NEW YORK.

KNIFE.

Application filed June 10, 1925. Serial No. 36,204.

This invention relates to a knife of the type known as clasp knives, and one object of the invention is to provide a knife having a pivotally mounted blade which is 5 spring actuated so that it may be caused to move from a closed position with its cutting edge disposed in a pocket of the knife handle to an extended position for use when a latch which serves to retain the blade in 10 either a closed or extended position is moved to release the blade.

Another object of the invention is to so construct the knife that the actuating element of the latch will be disposed at one side 15 thereof where it may be conveniently pressed upon with the thumb when the knife is held in approximately the position for use. By this arrangement of parts, the knife when closed may be held in the hand 20 in the usual manner with the thumb in position to engage the actuating element of the latch and pressure applied by the thumb so that the blade will be released and thrown outwardly and upwardly to an ex- 25 tended position for use. This also permits the knife to be easily closed as it is simply necessary to tilt it so that, when the latch is pressed to a releasing position, the blade will of its own weight drop downwardly 30 and can then be easily moved into the closed position with one hand.

Another object of the invention is to so construct the knife that the latch may be almost entirely within the confines of the 35 handle and not be liable to catch when placed in the pocket or removed for use.

This invention is illustrated in the accompanying drawing, wherein—

Figure 1 is a view showing the improved 40 knife in side elevation;

Fig. 2 is a longitudinal sectional view through the knife with the blade in the closed position;

Fig. 3 is a longitudinal sectional view 45 with the blade extended for use, and

Fig. 4 is a transverse sectional view taken on the line 4—4 of Fig. 2.

Referring to the drawing, it will be seen 50 that the knife is of the class known as clasp knives and includes a handle which is indicated in general by the numeral 1 and a blade 2. The handle 1 is provided with side walls 3 which are formed of heavy metal and connected adjacent their rear ends by rivets 4 which also serve to retain the leaf 55 spring 5 in place between the walls. Re-

ferring to Fig. 2, it will be seen that the rivets 4 extend through the thickened rear end portion 5' of the leaf spring and that the leaf spring extends forwardly at an outward incline with its free end terminating in the position shown in Fig. 3 so that, when the blade which is pivotally mounted between the forward end portions of the walls 3 by a rivet 6 is swung to the closed position shown in Fig. 2, the heel portion 7 of the blade will engage the free end of the leaf spring 5 and compress the spring to the position shown in Fig. 2. The heel portion 7 of the blade is provided with a shoulder 70 extension 8 and a pin 9 is secured in the shoulder extension 8 with its end portions extending from opposite side faces of the shoulder. The extended end portions of the shoulder are adapted to contact with the 75 knife handle, as shown in Fig. 3, and limit movement of the blade in an opening direction and also brace the blade when extended for use. The knife is, therefore, of a compact construction and will be very 80 strong and durable.

In order to permit the blade to be secured in either a closed or an extended position, there has been provided a latch which is formed of resilient metal and includes a 85 strip 10, one end portion of which is curved longitudinally and terminates in a hook 11 adapted to engage the butt or heel end of the spring 5, as shown in Figs. 2 and 3. The strip 10 extends between the side walls of 90 the knife handle and is of such thickness that its outer face is substantially flush with the edge faces of the handle walls or plates 3 at the back of the knife. The bolsters 12 have their rear portions cut away to provide 95 pockets 13. These pockets 13 are in advance of the forward ends of the ornamental pieces 14 secured against the outer faces of the side walls or plates 3 of the knife handle and are adapted to receive side arms 15 and 16 which extend from the forward end portion of the spring strip and are bent to 100 extend into the pockets, as shown in Fig. 4. Recesses 17 are provided in the plates 3 so that the arms may be bent into the pockets. It should be noted that since the pockets 13 and arms 15 and 16 do not extend the full 105 width of the bolsters 12 the free end portions of the arms will be covered and, therefore, dirt will be prevented from readily working 110 into the space between the arms and the outer faces of the plates 3. The arms may,

therefore, move freely and the latch may be very easily actuated when it is desired to release the blade. A pin 18 extends inwardly from the arm 15 and projects through an opening 19 in one of the plates 3 into position for engaging the heel of the blade 2 and entering the sockets 20 and 21 formed in diametrically opposed relation to the pivot pin or rivet 6.

Under normal conditions, the blade 2 is closed and will have its cutting edge disposed within the longitudinally extending pocket of the knife handle. When it is desired to use the knife, it is held in one hand with the end portion provided with the bolsters 12 extending forwardly and the arm 16 in position to be easily pressed by the thumb. Pressure is then applied to the arm 16 and this causes the substantially U-shaped forward end portion of the latch to be tilted transversely of the handle. When this takes place, the arm 15 moves away from the handle and the pin 18 moves out of the opening or socket 21. The blade is, therefore, released so that the spring 5 which has been held under tension may act upon the heel of the knife blade and cause the knife blade to be swung outwardly to the extended position for use. Outward movement of the blade beyond the position shown in Fig. 3 is prevented due to the fact that the end portions of the abutment pin 9 will contact with the handle. When in the extended position, the pin 18 will enter the socket 20 and the blade will be securely held and cannot accidentally move towards a closed position with consequent danger of the person using the knife becoming cut. When the knife is to be closed, it is simply necessary to tilt the hand so that the blade extends at an incline and then press upon the arm 16 so that the latch pin is moved out of the socket 20 and the blade allowed to drop of its own weight. The heel will strike the free end portion of the leaf spring 5 so that its closing movement is checked and, therefore, there is no danger of the knife entirely shutting while the fingers of the user are in the way. After the blade has dropped to a partially closed position, the frictional contact between the pin 18 and the side face of the heel will retain it in its position and it is simply necessary to press upon the back of the blade and force it to the completely closed position shown in Fig. 2 in which position it will be again secured by the latch pin. There has, therefore, been provided a knife of the self-opening type which will be very convenient to handle as it may be very readily operated with one hand.

Having thus described the invention, I claim:

1. A knife comprising a handle provided with a longitudinally extending pocket, a

blade carried by said handle and movable from a closed position with its cutting edge within the pocket to an extended position for use, and latch means adapted to releasably secure said blade in an adjusted position, said latch being carried by said handle and including an actuating element extending in overlapping relation to a side wall of the handle from the back of the handle towards the front thereof and movable towards and away from the side wall.

2. A knife comprising a handle provided with a longitudinally extending pocket open along the front of the handle, a blade carried by said handle and movable from a closed position with its cutting edge within the pocket to an extended position for use, latch means adapted to releasably secure said blade in an adjusted position, said latch being carried by said handle and including an actuating element extending in overlapping relation to a side wall of the handle from the back of the handle towards the open front thereof and movable towards and away from the side wall, and a blade-engaging element movable through the other side wall of the handle into and out of position for locking engagement with the blade.

3. A knife comprising a handle having a longitudinally extending pocket open along its front, a blade carried by said handle and movable from a closed position with its cutting edge within the pocket to an extended position for use, and latch means carried by the back of said handle and including an arm extending towards the front of the handle in overlying relation to one side wall thereof and having a tooth extending through said wall to engage the blade and lock the blade in a set position, said arm being movable towards and away from said wall to move its tooth into a position for locking engagement with the blade.

4. A knife comprising a handle provided with a longitudinally extending pocket, a blade carried by said handle and movable from a closed position with its cutting edge within the pocket to an extended position for use, and latch means carried by the back of said handle and extending forwardly therefrom and movable transversely of the handle and including a tooth movable through a side wall of the handle into and out of position for locking engagement with the blade.

5. A knife comprising a handle provided with a longitudinally extending pocket opening through the front of the handle, a blade pivotally mounted at one end of said handle for swinging movement from a closed position with its cutting edge within the pocket to an extended position for use, a spring in the pocket of said handle adapted to be compressed when the blade is closed

- and serve to throw the blade outwardly to the extended position, and a latch carried by the back of said handle and including side arms extending forwardly from the back of the handle in overlapping relation to side walls of the handle towards the front thereof and movable towards and away from the side walls of the handle, one arm being provided with a tooth extension projecting through the adjacent side wall of the handle to engage the blade and secure the blade in either a closed or an extended position and the other arm constituting an actuating lever normally extending in diverging relation to the adjacent side wall of the handle and when pressed towards the adjacent wall of the handle causing the other arm to be moved to draw its tooth extension out of locking engagement with the blade.
6. A knife comprising a handle provided with a longitudinally extending pocket opening through the front of the handle, a blade pivotally mounted at one end of said handle for swinging movement from a closed position with its cutting edge within the pocket to an extended position for use, a spring in the pocket of said handle having a heel portion secured between the side walls of the handle and a free portion extending longitudinally of the back and adapted to be compressed when the blade is closed and serve to throw the blade outwardly to the extended position, and a latch including a resilient strip constituting the back of said handle and having one end portion secured to the heel portion of said spring, and side arms extending from the free end portion of said strip in overlapping relation to the side walls of the handle towards the front thereof and movable towards and away from the handle, one arm being provided with a tooth extending through the adjacent side wall of the handle to engage said blade and secure the blade in an adjusted position and the other arm constituting an actuating lever for imparting rocking movement to the latch transversely of the handle and draw the pin out of position for locking engagement with the blade.
7. A knife comprising a handle provided with a longitudinally extending pocket opening through the front of the handle, a blade pivotally mounted at one end of said handle for swinging movement from a closed position with its cutting edge within the pocket to an extended position for use, a spring in the pocket of said handle adapted to be compressed when the blade is closed and serve to throw the blade outwardly to the extended position, said blade having its pivoted end portion provided with sockets in diametrically opposed relation to the point of pivotal mounting for the blade, and a U-shaped latch straddling said handle with its arms extending along the sides of the handle, said latch being movable transversely of the handle and having one of its arms provided with a pin adapted to fit into the sockets of said blade and secure the blade in an adjusted position.
8. A knife comprising a handle provided with a longitudinally extending pocket opening through the front of the handle, a blade pivotally mounted at one end of said handle for swinging movement from a closed position with its cutting edge within the pocket to an extended position for use, a spring in the pocket of said handle adapted to be compressed when the blade is closed and serve to throw the blade outwardly to the extended position, said blade having its pivoted end portion provided with sockets in diametrically opposed relation to the point of pivotal mounting for the blade, a latch carried by said handle, said latch being formed of resilient material and including a strip extending along the back of said handle, side arms extending from said strip across the sides of said handle and movable towards and away from the handle when actuated, and a pin carried by one arm and extending into the pocket through a side wall thereof and adapted to fit into the sockets of said blade to releasably retain the blade in closed and extended positions.

In testimony whereof I affix my signature.
